UNITED STATES PATENT OFFICE

HERBERT SHERWOOD AKERS, OF MONTVALE, NEW JERSEY, ASSIGNOR TO THE KNY-SCHEERER CORPORATION OF AMERICA, OF NEW YORK, N. Y., A CORPORATION OF NEW YORK

DIATHERMY

Application filed June 2, 1928. Serial No. 282,490.

My invention relates to an improvement in a diathermy and its novelty lies in the adaptation and arrangement of parts as will be more fully hereinafter pointed out.

There are many forms of devices adapted for therapeutic diathermy but there is none adapted to the treatment of venereal diseases such as the gonococci germs which in the male lie along the urethral tract.

10 In order to reach such germs and kill them in an efficient manner it is necessary to raise the temperature along that portion of the urethral tract to a temperature sufficient to kill all of the germs.

15 This is a very difficult problem because of the inaccessibility of the urethral tract and my device is adapted to and has in actual use overcome the weaknesses of the entire prior art and has effectually killed all gonococci 20 on one application in mild cases and on two or three applications even in the most persistent cases because of the novel feature of applying intense heat throughout the entire length of the urethral tract.

25 Referring to the drawings Figure 1 is a side elevation of my device partially broken away in order to show all of the construction and in use on a patient with a medical table.

Figure 2 is a side elevation of the jar used 30 in my combination.

Figure 3 is a vertical section of Figure 2.

Figure 4 is a top plan view of an electrode used in my combination.

In the drawings 5 is a table in which is 35 suspended a glass jar 6 having an upper inset nipple 7 to which is connected a tube 8 having at its outer end a funnel 9 mounted therein and which is adapted to be held on the outer edge of the table 5 in bracket 10. A 40 lower outlet nipple 11 is also mounted on the jar 6 and an outlet tube 12 having a shut off valve 13 of usual construction adapted to carry off any waste from the jar 6 to a waste container 14.

45 The jar 6 has an electrode 15 connected by a wire 16 to a source of power not shown and an electrode 17 is connected in the usual manner by wire 18 to the source of power not shown.

50 A patient 19 lies on his stomach on the

table 5 so that penis 20 hangs into the jar 6. Water 21 in the jar 6 is then added to or drawn off through funnel 9 or by opening valve 13 respectively until the level of the water just contacts perfectly with the lower end of penis 20. The electrode 17 is then applied to the back of the patient in line with jar 6 and as the usual diathermy high voltage and low ampere current is turned on through the wires 16 and 18 it passes from wire 16 through electrode 15, water 21, penis 20, body 19 to electrode 17, wire 18 and back to source.

55 By this high voltage current through the entire length of the penis 20 and through the body 19 to the electrode 17 the entire urethral tract is gradually heated to a point whereby all gonococci germs throughout the entire urethral tract are killed.

60 It is to be noted that my construction is such that water may be added to or withdrawn from the jar 6 while the patient is in position for treatment and without disturbing him so as to insure the exact height of water necessary for carrying out the operation of my diathermy.

65 I claim:

1. In a diathermy apparatus the combination in the usual circuit of an electrode adapted to contact with the patient's back, a second electrode comprising a container holding water and means for varying the height of said water without disturbing the patient whereby sufficient heat is produced diathermically throughout the male urethral tract to insure the killing of gonococci germs.

70 80 85 90 95 100

2. In a diathermy apparatus the combination in the usual circuit of electrode means for effecting sufficient heat throughout the male urethral tract to kill gonococci germs comprising an electrode adapted to contact with the patient's back, a second electrode comprising a container holding water and means for varying the height of said water without disturbing the patient to insure exact contact with the outer end of the male organ whereby the required heat is insured for the entire length of the male organ.

In testimony whereof I affix my signature.

HERBERT SHERWOOD AKERS.
